SHOCKPROOF RADIOGRAPHIC TUBE

Malvern J. Gross and Zed J. Atlee, Chicago, Ill.,
assignors to General Electric X-Ray Corpora-
tion, a corporation of New York

Application March 22, 1935, Serial No. 12,428

13 Claims. (Cl. 250—88)

The present invention relates to X-ray apparatus and particularly to an improved insulating and cooling jacket for an X-ray tube.

The objects of the invention include, among others, the provision of:

An X-ray tube so protected that it is capable of withstanding large amounts of energy and operating efficiently within a body of oil or similar cooling and insulating material;

An enclosure for an X-ray tube arranged to hold insulating oil within a grounded metallic casing and providing means for taking up the expansion of the insulating oil under heat, such means to include either an expansion chamber containing an expansion and contraction device open to the atmosphere, or an ordinary expansion chamber connected to the tube enclosure by means of a conduit;

An X-ray tube having protection thereabout comprising a grounded casing completely enclosing the tube save for an opening provided for the emergence of a useful beam of X-light;

Means for positioning and locating an X-ray tube so that it may be accurately located within a container;

A novel cathode base for an X-ray tube so arranged that the contact points covered by it can be adjusted after the base has been cemented or otherwise affixed to the tube;

A novel arrangement of insulators and connectors whereby electrical energy for activating an X-ray tube may be carried within the body of a casing; and

A novel radiator for removing heat from the anode of a tube and so designed that it will give a maximum volume to the radiator while imposing a minimum strain on the insulation between the radiator and the inner surface of the container.

These objects and such other objects as may hereinafter appear are obtained by the novel construction, unique arrangement and improved combination of elements which constitute the invention, one form of which is illustrated in the accompanying three sheets of drawings hereby made a part of this specification.

In the drawings:

Figure 1 is a transverse section of a tube and a housing therefor constructed in accord with the invention.

Figure 2 is an exploded perspective of the cathode energizing and tube locating means shown in the section at the left hand side of Figure 1.

Figure 3 is a transverse section along the line 3—3 of Figure 1.

Figure 4 is a transverse section of one of the cables made in accordance with the invention and taken along the line 4—4 of Figure 1.

Figure 5 is a perspective view of the protecting collars and locks used at the ends of the X-ray tube.

Figure 6 is a diagrammatic representation of the circuits to a tube having exterior to the tube 10 casing a switching device for energizing one cathode or the other, an expansion device being shown attached to the casing.

Figure 7 is a view similar to that in Figure 6 but with the change-over or switching device 15 disposed within the casing and the expansion device separate from the casing but connected thereto by means of a flexible tubing.

Like reference characters are used to designate similar parts in the drawings and in the description that follows.

Reference should be had first to Figure 1. A container 10 encloses an X-ray tube 11. The X-ray tube 11 has an anode 12 and a cathode 13. The anode comprises an anode head 14 made of 25 copper or other suitable material in which a tungsten button 15 is embedded in a manner well-known in the art. The head 14 is upon a shank 16 and is attached thereto in any suitable manner, as for instance, by means of the complemental screw threads 17.

The shank 16 has a passage 18 to permit air to escape from between the anode head 14 and the forward end of the anode shank 16 as these two parts are assembled by screwing one into the other. The passage 18 is provided so that close and intimate contact may be had between the opposing surfaces of the anode head 14 and anode stem 16.

A nickel steel sleeve 19 is attached to the anode head 14 in any manner desirable, such as by soldering. The sleeve 19 may be made in accordance with the particulars given in a copending application for Letters Patent, entitled X-ray tube, Serial Number 715,902, filed March 16, 1934 by Malvern J. Gross and Zed J. Atlee, and comprises a satisfactory jointure between the glass of the tube and the metal portions of the anode. The glass to metal joint between tube and sleeve is indicated at 20. In the manner illustrated, the anode head 14 and with it the anode shank 16 are supported within the envelope of the X-ray tube.

A second metallic tube or sleeve 21 also made of nickel steel or other suitable metal is secured 55

to the anode head 14 in any desirable manner, as for instance, by means of screws 22. The tube or sleeve 21 aids in blocking up the anode arm of the X-ray tube and also shields the glass-to-metal joint 20 from stray electron bombardment which might cause disintegration of the glass to metal seal.

The tube has an envelope 23 which comprises an anode extension 24 having a reentrant portion 25 to which the glass-to-metal seal 20 is made. The envelope includes an enlarged central section 26 which forms what is known as the bulb portion of the tube.

Opposite the anode extension 24, there is a cathode extension 27. Extension 27 has a reentrant portion 28 in which an inverted pinch seal 29 is located. The seal-off of the tube is indicated at 30.

The pinch seal 29 is made in a manner well known in the art. Through it passes conductors for energizing the filaments forming a portion of the cathode that will be described later.

The cathode 13 consists essentially of a cathode cup 31. The cathode cup 31 has a plurality of filaments, 32 and 33. These filaments are for the purpose of converting the X-ray tube from one having a large focal spot and using a high energy unit to a tube having a small focal spot and employing a small energy unit, or vice versa, for purposes which are well understood by any one skilled in the X-ray art.

While the drawings illustrate but two filaments and hence the possibility of two focal spots of different sizes, it is to be understood that a construction similar to that shown may be readily made to increase the number of focal spots to say, three, four, five, or more.

The filaments 32 and 33 are surrounded by depressed focusing openings 34 and 35, respectively, the cups being constructed and operating in a manner well-known in the art. Circuits for use with the several filaments 32 and 33 will be more fully described later in this specification in connection with a device herein disclosed for shifting energy from one filament to the other.

The cathode arm 27 of the X-ray tube has attached to it, as by cementing or any similar process, a cup 36, to which a plate 36a is attached by means of screws 190, which pass through arc-shaped slots 191 in the plate 36a and are screwed into threaded holes in bosses in cup 36. The arc-shaped slots 191 are made somewhat wider than necessary for the screws 190, so as to permit adjustment of the plate 36a on the cup 36 in a single plane for a purpose later to be described.

Plate 36a has located on it contact points 37, 38, and 39 (see Figure 2) to which the terminals of the two filaments 32 and 33 are connected.

The tube enclosure or casing 10 consists essentially of an outer body 40 of a conductive material such as aluminum. The inner surfaces of the enclosure or casing 10 are sealed against oil leakage by means of several coats of a suitable material or compound such as Glyptol, Bakelite varnish, etc. Such sealing material is indicated 41. The casing 40 has a central section 42 of a generally cylindrical form and two irregular shaped end pieces of larger diameter, 43 and 43a, respectively.

The central cylindrical section 42 forms a main support for the X-ray tube 11. An insulating sleeve 44 of Bakelite or similar material closely surrounds the bulb section 26 of envelope 23 of the X-ray tube. Sleeve 44 has about it a

second sleeve 45 of shorter length and made of lead or any other suitable X-ray absorbing material. The sleeve 45 is for arresting the primary radiation from the X-ray tube. An aperture 46 is formed at a suitable spot in the protective sleeve 45 to permit of the passage of a cone of useful X-rays from the tube.

The sleeves 44 and 45 are cemented together and to the casing 10. They are also held in position mechanically by means of a plug 108, having a turned down end which fits in the aperture 46 in sleeve 45. The plug 108 is held in position on the casing in a manner which will be explained later.

Spaces shown at 46a are provided between the container 10 and sleeve 45 to permit of the passage of oil from one section of the container 10 to the other. The insulating sleeve 44 supports at the end closest to the cathode of the tube a support casting 45a.

Support casting 45a has within its inner surface lugs 46b for the purpose of supporting and locating an alignment plate 47 (see Figure 2), which is secured to the lugs 46b by means of screws 48. The alignment plate 47 has located within it three apertures 49 which are sufficiently large to permit of the passage of the pins or contacts 37, 38, and 39 therethrough. The apertures 50 which are only large enough to permit the passage of the necks 51 of the three pins or contacts 37, 38, and 39, are connected to the three apertures 49 by arcuate slots 52.

Because of this arrangement, the cathode end of X-ray tube 11 may be pushed back inside the sleeve 44 until the pins 37, 38, and 39 register and pass through the holes 49 in the plate 47, after which the X-ray tube may be twisted, the necks 51 of the pins 37, 38, and 39 following the course of the slots 52. The pins or contacts 37, 38, and 39 are then held in engagement in the holes 50, the enlarged heads of the pins preventing disengagement of the tube from the plate 47.

Circuits are then established to pins 37, 38, and 39 by means of the contact plate 53 which has three contacts 54, 55, and 56, complementary to pins 37, 38, and 39. Connections are made to contacts 54, 55 and 56 in a manner which will be described later.

The contact plate 53 floats on a stud 57 on plate 47. The contact plate 53 has an aperture 58 through which the stud 57 projects. The contact plate 53 is urged into contact with pins or contacts 37, 38, and 39 by means of a spring 59. One end of spring 59 abuts the contact plate 53 and its other end engages end member 62 having a boss 68, the spring engaging the inner face of boss 68. The end member or cover plate 62 closes the end of the sleeve 44 and is held in position by means of the screw 61 which is threaded into stud 57.

Protection against the radiation emitted from the end of the X-ray tube is had by means of rings 63 of suitable material which are held in position by means of a clamping ring 64 fastened by screws 65 (see Figure 5).

The upper part of the enlarged section 43a of the envelope terminates in a receptacle 70 through which conduits carrying current are carried to the interior of the enclosure or container 10. The current for energizing the several filaments of the tube and also the high tension current for the tube proper is carried by an insulated cable 71 shown in transverse section in Figure 4.

In that figure, there is a plurality of wires 72 inside the cable and insulated one from another. The wires 72 carry one side of each of the separate filament energization circuits when a change-over switch for connecting either one filament or the other is exterior of the tube container 10, as is the case in the form of the invention shown in Figure 6.

In the drawings, only two conductors 72 are indicated; these to conform with the two-filament tube illustrated and herein described. If three filaments were used in the tube, the series of conductors 72 would comprise three separate elements; if four filaments, then four separate conductors would be shown, etc.

Spaced a slight distance away from the inner conductors 72 and insulated therefrom is a circle of smaller conductors 73. The conductors 73 are connected one to another and form a common lead for all of the various filament circuits. The conductors 73, as can be seen, are spaced closely together to form as far as is possible a corona-proof surface and to reduce to a minimum the possibility of breakdown of the insulation. This is essential in the building up of cables for the voltages used. Irregular spacing or misalignment of the conductors 73 may cause breakdown at much lower voltage than is the case when the conductors 73 are evenly and regularly spaced in the manner described.

Surrounding the conductors 73 just described is a main insulating body 74 of corona-proof rubber or similar material. Exterior of body 74 is a metallic sheath 75 which is at ground potential and serves as an automatic safeguard against shocking the operator or patient should a breakdown of the insulation occur.

The cable just described and designated as a whole as 71 terminates within an insulating sleeve 40 76 (see Figure 1). The sleeve 76 is sealed to the cable by means of an insulating material with which the end of the cable 71 to be placed within the sleeve 76 is coated after the metallic sheath 75 of cable 71 has been removed as is indicated 45 at 77. The sleeve 76, at its lower end, has three connecting bushings 78.

The connecting bushings 78 comprise three studs 79 through each of which a small aperture 80 extends. The studs 79 are secured in position by means of nuts 81. The free end of the conductors 72 and of conductors 73 are carried through the holes 80 in the studs 79 after which they are soldered as shown at 82. Connections are then made between the studs 79 and the contact posts 54, 55, and 56 upon plate 53 by means of several separate conductors 83.

The insulator 76 and the cable 71 are held in position on the casing 43a by a clamp 84 which surrounds the insulator 76 and is held in engagement with casing 43a by screws 85. A split brass sleeve 86 is soldered over the free end of the ground sheath 75 terminating at 77, and the cable 71 is clamped in position on the sleeve 86 at this point by means of screw 87.

The reason for the particular structure just recited has its basis in the action of oil on rubber insulation, particularly when the oil is hot. When oil comes into contact with rubber insulation an interaction takes place which destroys the rubber and causes a breakdown of the insulation. In the construction described, the sealing of the cable into insulating sleeve 76 prevents this interaction and so provides a structure having permanent insulating qualities.

A cable 90 extends to the anode. Cable 90

is similar in construction to cable 71 except that only a single lead is used. The single lead comprises the inner and outer ring of conductors which are electrically connected so as to maintain them at the same potential. The combination of the several conductors is soldered to a conductor button 91 projecting from the end of the cable 90. An insulating sleeve 92 similar to sleeve 76 is attached to the cable 90. The insulating sleeve 92 has at its end a shouldered bushing 93. A plunger 94 projects from the lower end of bushing 93 and is maintained against movement entirely out of the bushing 93 by a shoulder 95. A spring 96 is compressed against the plunger 94 and is held on the bushing 93 by a threaded sleeve 97 which terminates in a prong 98 that grips and makes contact with the conductor button 91. Thus current is carried from the several conductors in cable 90 to the spring actuated plunger 94 that makes contacting engagement 20 with a radiator 99.

The object of radiator 99 is to rapidly absorb heat energy from the anode head 14 and to store such heat energy until it can be transmitted to the surrounding oil. It is important 25 that this radiator be as large as possible, not only for the purpose of increasing its heat absorption capacity, but also to give it an outer diameter as nearly as possible equal to the inner diameter of the container, so as to reduce to a 30 minimum the space between the radiator and the inner surface of the container. The surface of the radiator should be of substantially uniform curvature, without points or corners, and the radius of the curvature should be always as great as possible. The end sought by this construction is to increase as far as possible the transfer of heat from the radiator, through the oil and to the wall of the container, from which point radiation to the surrounding atmosphere 40 takes place, while not decreasing the maximum operating voltage of the tube. The radiator is fastened to the anode shank 16 by means of a set screw 100. A thrust screw 101 is provided for releasing the radiator 99 from the anode shank 45 16 when it is desired to separate the two.

The open ends of the container 10 are closed by means of two caps 102 and 103, one of which is provided with a filling opening 104 sealed by means of a threaded plug 105. Caps 102 and 50 103 are held in place in any desired manner as, for instance, by means of screws 106.

An opening 107 is provided in container 10 for the passage of a useful beam of X-rays. Opening 107 registers with opening 46. The opening 55 107 is sealed against oil leakage by means of the plug 108, previously mentioned, which has a center section 109 of extremely thin material to reduce to a minimum the absorption therein of X-rays. The plug 108 is secured in place by any suitable sealing compound and is mechanically held in position by means of screws 109a which pass through a shoulder 110 in the plug. Plug 108 also secures the sleeves 44 and 45 in position by extending into the aperture 46 in sleeve 45. 65 Surrounding the plug 108 and the X-ray opening is a lead cylinder 192 which fits against the outer diameter of the lead sleeve 45, for the purpose of aiding the absorption of primary radiation from the tube 11. The flaring sleeve 111 70 which surrounds the plug 108 and projects from the main body of the container is provided for the purpose of mounting the entire structure on any of the standard tube stands. Within the flaring sleeve is an additional protection cone 193 75

fastened in position by means of the screws as shown. The cone is for the purpose of absorbing unwanted primary radiation.

The expansion of oil in the container 10 presents a problem which is solved herein in two different ways.

The construction illustrated in Figures 1, 3, and 6, will be discussed first. In these figures, there is shown an oil expansion device having an outer casing 120 generally made of sheet metal and terminating at one end in a nipple 121 which screws into threads 122 in the container 10 surrounding the X-ray tube 11. An aperture 123 extends through the center of the nipple 121, thus connecting the inner portions of the container 120 and of the tube container 10. Casing 120 has thereon and supports an expansion device of the so-called "Sylphon" or bellows type. The expansion and contraction device comprises an accordion-like metallic structure 124 that has soldered to it at the upper end of the container 120, a stud 125. The lower end of the bellows 124 has an inner stud 126 into which a rod 127 is screwed. The arrangement described maintains the bellows device in proper alignment at all times and provides in the rod 127 a calibration means 128 for indicating temperature conditions (in terms of pressure) within the X-ray tube enclosure 10. A spring 129 urges the expansion device to its expanded position.

When the tube 11 is energized, insulating oil which fills the container 10 becomes heated as a result of the absorption by it of the heat energy of the tube. The oil expands under heat. The enlarged volume of the oil causes a portion thereof to push itself into the container 120 to contract the expansion and contraction bellows 124 against the action of the spring 129. Rod 127 is forced upwardly out of container 120 a greater distance as more oil forces itself into envelope 120. When the tube 11 is deenergized, the oil cools. The urge of spring 129 expands the expansion and contraction device 124, thus compensating for the reduction in oil volume and maintaining the container 10 about the tube 11 free of voids. Freedom from voids is a condition essential for the safe operation of an X-ray tube.

The second form of device for compensating for oil expansion is shown in Figure 7 and comprises a container 130 connected to the container 10 by means of a flexible tube 131. When a container 130 is employed, an oil level gauge 132 is generally employed. The container 130 has a filling opening 133 closed by a plug 134 that contains an air vent 135 for relieving air pressure in tank 130.

The question of weight is of the greatest influence in deciding between the two methods just described for application to a specific installation. Where ease and rapidity of adjustment is of the greatest importance and some sacrifice of range can be made, the structure with the separate container is usually provided. If range is the prime essential the structure shown in Figures 1 and 6 is used. In this way, means are provided whereby the best possible combination for any particular purpose can be had while using a common basic construction.

One of the most difficult problems with respect to tubes of the variety illustrated is the proper alignment of the X-ray tube 11 with the opening in casing 10 for the passage of useful X-rays. Deviation from proper alignment can be in two

directions, namely, longitudinally of the casing, that is, in a direction parallel to the main axis of the tube, or axially, that is, the tube may be improperly positioned in angular direction when considering the longitudinal axis of the tube as the center of rotation. Possibility of both of these errors is avoided in the construction illustrated.

Accurate longitudinal adjustment of the tube in the container is provided for by the cathode 10 cap 36 and plate 36a. During the manufacture of the tube, the base may be adjusted back and forward on cathode arm 27 until a proper position is obtained. In practice, a certain dimension is set up as being accurate for spacing the center of the anode button 15 from some predetermined point on the plate 36a. The plate 36a is positioned in accordance with this dimension. Plate 36a and cap 36 are properly positioned angularly and the cap 36 with plate 36a attached is cemented in place.

Axial registry of tube and casing is provided for by the structure shown in Figure 2. It is a simple matter to position the pins or contacts 37, 38, and 39 in a definite relation to the cathode openings 34 and 35 in the cathode 13 by moving plate 36a on cap 36, screws 190 moving in slots 191 to permit the shift. In the same fashion, the support casting 45a can be definitely positioned in respect to bakelite sleeve 44 which in turn is held in a definite relation with respect to the X-ray opening 46 by plug 188. The line thus obtained definitely positions the alignment plate 47 which determines the angular position of the tube when in operable position.

Selection and energization of any one of the several filaments in the X-ray tube 11 may be had in one of two methods. These are shown in detail in Figures 6 and 7.

Figure 6 illustrates a structure in which the switching mechanism is external of the tube. In Figure 6, a transformer 150 is illustrated and is the source of a high tension current.

One terminal of secondary 151 of transformer 150 is connected through cable 90 to the anode 12 of X-ray tube 11. The other terminal of transformer 150 is connected through cable 71 to the cathode 13 of X-ray tube 11. A filament current transformer 152 is also shown. Secondary 153 of the transformer 152 is connected at one end to a pivot point 154 in a movable contact 155 of a hand-operated switch mechanism 156. The other terminal of the secondary 152 is connected to one terminal of secondary 151 and from thence to a common lead 157 for both filaments in the tube.

The outer lead of one of the filaments 158 is connected through cable 71 to a resistance 159 and thence to a contact 160 of the switch mechanism 156. The other terminal of the other filament 161 is connected to another contact 162. An insulated pusher bar 163, actuated in any desired fashion as, for instance, by a cord system, is arranged to move the movable contact 155 from one point to the other as desired. From this it can be seen that either one of the two filaments provided can be selected for operation. The bar 163 may be used to indicate which filament is lighted.

The filament current switch 156 may be located wherever desired. It is generally hung in the filament transmission system at the end of the cable 71. This, however, is immaterial, and it could be interposed in any point in this cable just as readily.

When a separate selecting switch is thought undesirable, an arrangement similar to that shown in Figure 7 may be employed. Only two leads are carried to the cable 71. In this device, a high tension transformer 170 supplies high tension current for energizing the X-ray tube 11. Secondary 171 in the high tension transformer 170 has one terminal connected through cable 90 to the anode 12 of the X-ray tube 11. The other terminal is carried through cable 71 to the anode lead 173 of the tube filaments in the X-ray tube.

A filament current transformer 174 is provided for supplying filament current. The secondary 175 of the filament current transformer has one side connected in common to one terminal of the high tension secondary and is with this terminal connected to the lead 173 of the two filaments. The other terminal of the filament current transformer secondary 175 is connected to the two upper contacts 176 of the switch mechanism 177. One lower contact 178 is connected to the other terminal of one of the filaments, as shown at 179 through resistance 179a. The other lower contact 180 is connected to the remaining terminal of the other filament as shown in 181.

The movable member of the switch consists of an insulating pusher rod 182 provided with a conductive cylinder 183 arranged to connect contacts 176 and 178 or contacts 176 and 180 together in order to select the desired filament for the operation. Actuation of pusher rod 182 is had through accordion-like expansion and compression devices 184 and 185 secured to the outer casing of the tube at opposite ends of rod 182.

The expansion and contraction devices 184 and 185 are secured to the casing to provide oil-tight joints between the casing and said expansion and compression devices and at the same time, through the medium of their expansibility and compressibility, to permit of the actuation of the pusher rod 182 for selectively establishing the desired filament circuit. For this arrangement, only two conductors need be brought down the cathode cable, and no auxiliary mechanisms exterior of the tube are required.

From the foregoing, it is seen that there has been devised an X-ray tube which is entirely enclosed within a grounded metallic casing. Danger of electrical shock thus is avoided. X-ray protection has been provided in the form of a lead cylinder about the body of the X-ray tube and in rings made of lead impregnated insulating material about the anode and cathode arms of the tube. In order to reduce the size of the container, oil has been supplied as a dielectric. Two different methods are illustrated for taking care of the unavoidable expansion of the insulating oil due to increases in temperature of the oil during operation of the X-ray tube. Means have been disclosed whereby the X-ray tube can be readily positioned lengthwise of a casing and in correct axial direction thereto to permit accurate registration of the focal spot of the tube with an aperture in the casing for the passage of radiation. A novel method of bringing in the high tension current to the X-ray tube has been provided. The X-ray tube shown is of the double focus type. Two methods for selecting the filament of such X-ray tube to be energized have been disclosed, one of these being with the selector switch at the exterior of the casing, and the other with the switch an integral part of the casing.

What is claimed as new and is desired to be secured by Letters Patent of the United States is:

1. In combination, an X-ray tube, an X-ray transparent insulating sleeve fitting closely thereabout, a sleeve of material opaque to X-light about said insulating sleeve and having an aperture for the passage of a pencil of useful X-rays, a tube enclosing casing having an aperture registering with the aperture in said sleeve of opaque material, and a plug having a window 10 therein and inserted into the apertures in said casing and said opaque sleeve for retaining the opaque sleeve and casing in proper alignment.

2. In combination, a high tension transformer, an X-ray tube, having an anode and a cathode, 15 high tension conduits from said high tension transformer to said anode and cathode, two filaments in said cathode, a filament current transformer, a first filament current conduit from one terminal of said filament current transformer 20 common with the high tension conduit to said cathode and common to both of said filaments, a second filament current conduit from said filament current transformer, third and fourth filament current conduits each leading to a different filament, switch means for selectively connecting the second of said conduits to said third and fourth conduits to determine the filament to be energized, and a casing for enclosing said tube and said switch.

3. In combination, a high tension transformer, an X-ray tube, having an anode and a cathode, high tension conduits from said high tension transformer to said anode and cathode, two filaments in said cathode, a filament current transformer, a first filament current conduit from one terminal of said filament current transformer common with the high tension conduit to said cathode and common to both of said filaments, a second filament current conduit from said filament current transformer, third and fourth filament current conduits each leading to a different filament, switch means for selectively connecting the second of said conduits to said third and fourth conduits to determine the filament to be energized, a casing for enclosing said tube and said switch, an operating rod for said switch traversing said casing, and compressible means on said casing enclosing the ends of said rod.

4. In the combination of claim 3 wherein the compressible means comprises closed end bellows sealed upon the side of said casing and enclosing the ends of said rod projecting from said casing.

5. In combination, an X-ray tube having an anode and a cathode, a casing for said tube, said casing having an X-ray transmitting window portion, a cap on said tube at a predetermined distance from said anode, contact members carried by said cap, a holding member, and means for supporting said holding member on said casing in a predetermined position and at a predetermined distance from said window portion, said holding member having arcuate apertures to slidingly receive said contact members upon partial rotation of said tube whereby the anode is properly aligned relative to the window portion of the casing and said tube is locked against axial movement relative to said casing.

6. The combination as defined in claim 5 and in which the contact members carried by the cap have enlarged heads, and the arcuate apertures in said holding member are each enlarged at one end to receive one of said enlarged heads.

7. In combination, an X-ray tube having an anode and a cathode, a casing for said tube, said casing having an X-ray transmitting window portion, a cap on said tube at a predetermined distance from said anode, contact members carried by said cap, a holding member, means for supporting said holding member on said casing in a predetermined position and at a predetermined distance from said window portion, said holding member having arcuate apertures to slidably receive said contact members upon partial rotation of said tube whereby the anode is properly aligned relative to the window portion of the casing and said tube is locked against axial movement relative to said casing, and a terminal plate loosely mounted on said holding member and having a plurality of contact members adapted to engage the contact members on said cap when said tube is in locked position.
8. In the combination defined in claim 7 wherein resilient means are provided for retaining said terminal plate on said holding member and for normally urging the contact members on said terminal plate into engagement with the contact members on said cap.
9. In combination, an X-ray tube comprising an envelope and an anode and a cathode in said envelope, a casing for said tube, said casing having an X-ray transmitting window portion, a dielectric sleeve interposed between said casing and said tube, a cap on the cathode end portion of said tube at a predetermined distance from the anode, contact members on said cap, a supporting member carried by said sleeve adjacent one end thereof and spaced a predetermined distance from the X-ray transmitting window portion of the casing, a holding member having arcuate apertures to slidably receive said contact members, said arcuate apertures each being enlarged at one end to freely receive said contact members whereby upon insertion of said contact members into said apertures, and upon partial rotation of said tube, the anode is properly aligned relative to the window portion of the casing and the tube is locked against axial movement relative to said casing.
10. In combination, an X-ray tube comprising an envelope and an anode and a cathode in said envelope, a casing for said tube, said casing having an X-ray transmitting window portion, a dielectric sleeve interposed between said casing and said tube, a cap on the cathode end portion of said tube at a predetermined distance from the anode, contact members on said cap, a supporting member carried by said sleeve adjacent one end thereof and spaced a predetermined distance from the X-ray transmitting window portion of the casing, a holding member having arcuate apertures to slidably receive said contact members, said arcuate apertures each being enlarged at one end to freely receive said contact members whereby upon insertion of said contact members into said apertures, and upon partial rotation of said tube, the anode is properly aligned relative to the window portion of the casing and the tube is locked against axial movement relative to said casing.
11. In combination, an X-ray tube, a metal casing for enclosing and supporting said tube, X-ray opaque and X-ray transparent sleeves interposed between said casing and said tube and in engagement with said tube and casing for supporting said tube upon said casing, said casing and said X-ray opaque sleeve having registering apertures to permit the emission of a useful beam of X-rays from said X-ray tube, a plug secured to said casing and extending into the aperture in said opaque sleeve for retaining the opaque sleeve and casing in proper alignment, said plug having an X-ray transparent window therein in alignment with the registering apertures in said casing and opaque sleeve, and said X-ray transparent sleeve being of insulatory material and having a portion extending across the opening in said opaque sleeve and said casing.
12. The combination of claim 11 including an insulating fluid in said casing, said casing having a groove extending circumferentially partially about said opaque sleeve and axially thereof the full length of said opaque sleeve to form a passage permitting free circulation of the insulating fluid from end to end of the casing.
13. In combination, an X-ray tube having an envelope, a casing enclosing said envelope, laminations of electrically insulatory and non-insulatory material interposed between said casing and said envelope, one of said laminations of the casing being opaque to X-light and having a window for the emission of a beam of useful X-light and another lamination being closely circumjacent said envelope and of a dielectric material transparent to X-light, said dielectric lamination having a continuous extension across the window formed in the opaque lamination, through which extension the beam of useful X-light is projected, said casing having an opening therein in registry with the opening in said opaque lamination and a plug having an X-ray transmitting window therein, said plug being secured to said casing and extending into the opening in said casing and the opening in said opaque lamination for retaining the opaque lamination and casing in proper alignment.
